(57) **CLAIM**

The ornamental design for a tablet case back, as shown and described.

DESCRIPTION

FIG. 1 is a front, top perspective view showing an embodiment of a tablet case back.

FIG. 2 is a front elevational view of FIG. 1;

FIG. 3 is a rear elevational view of FIG. 1;

FIG. 4 is a right elevational view of FIG. 1;

FIG. 5 is a left elevational view of FIG. 1;

FIG. 6 is a top plan view of FIG. 1; and,

FIG. 7 is a bottom plan view of FIG. 1.

The broken lines immediately adjacent the shaded areas represent the bounds of the claimed design while all other broken lines are directed to environment and are for illustrative purposes only; the broken lines form no part of the claimed design.

1 Claim, 5 Drawing Sheets
